UNITED STATES PATENT OFFICE.

CHARLES RALEIGH, OF JERSEY CITY, NEW JERSEY, AND WILLIAM V. D. KELLEY, OF BROOKLYN, NEW YORK, ASSIGNEES, BY MESNE ASSIGNMENTS, TO PRIZMA INCORPORATED, A CORPORATION OF MAINE.

COLOR PHOTOGRAPHY.

1,325,204.

Specification of Letters Patent. Patented Dec. 16, 1919.

Application filed December 20, 1916. Serial No. 137,943.

To all whom it may concern:

Be it known that we, CHARLES RALEIGH, a subject of the King of Great Britain, and WILLIAM V. D. KELLEY, a citizen of the 5 United States, residing at Jersey City, county of Hudson, State of New Jersey, and Brooklyn, county of Kings, State of New York, respectively, have invented certain new and useful Improvements in Color 10 Photography, of which the following is a full, clear, and exact specification.

This invention relates to photography in colors, and has particular reference to the reproduction of motion pictures in natural 15 colors. The object of the invention is to provide a method, color screen, and image produced thereby, which while filtering the light to produce the various color value records on the emulsion will also as closely 20 as possible approximate the conditions of a colorless transparency in simultaneously passing the light.

In French Patent No. 479,921, granted February 29, 1916, there is disclosed a 25 method, screen, and image, wherein an exposure to white light and a color value record are superposed on the same section of emulsion, whereby the several component color records of the cycle are intensified or 30 leveled without destroying the difference in color value. According to said patent, there is a clear section associated with each fundamental color filter section so that each emulsion section is exposed both to the color section 35 to obtain the color value record, and to the clear or intensifying sector to obtain black and white values. By such apparatus and method, the resulting pictures are soft and pleasing in color, and owing to having 40 been intensified, are as complete in detail and depth as though an ordinary exposure made without color filters.

This invention relates to the same subject, but embodies an improvement in the method, 45 screen, and image, whereby a sudden transition from the color section to the clear section, or vice versa, is avoided by means of a graduated screen or filter, each section preferably uniformly shading from practically 50 clear (or open) to the full color depth for that section, or the color uniformly weakens to white or clear. This is useful in graduating the proportions of color and clear in each section, and also in balancing two,

three, four or more sections. The exposure 55 for any particular image begins by recording nearly all colors, or white light, but gradually and progressively reduces the intensifying white rays until only the desired predetermined or fundamental color is 60 passed by the screen and recorded on the emulsion. Or, the color can be recorded first and the intensifying values later if the screen moves in the other direction. One or more of the screen sections may be made in 65 this way, although it is preferable that all be so made. Sufficient color value differences are thereby obtained between the images of a series so that the original colors are reproduced when projected; less light is required 70 to obtain a good exposure than with known screens made up of uniform solid color; the series of pictures on the film are very much more uniform in appearance and intensity than where solid screen colors are used; and 75 the light admitted to the emulsion section at all times favors the desired color value.

The screen carrying the filters is movable for both still and motion color photography. The simplest form is a revolving screen as 80 herein illustrated, but it may reciprocate, or be embodied on an endless band, or in any other way, so that the filter screens move during the period of exposure. In a three color process, in which the images are suc- 85 cessively taken through three color screens, such as red, green, and violet, the screen is driven so that it moves one-third of its period for the red value image, one-third for the green value image, and one-third 90 for the blue-violet value image. The screen may also carry opaque sections between each color section to allow for the shifting of the film, or an auxiliary cut-off shutter may be used to perform this function, according to 95 well known practice.

In the accompanying drawings,

Figure 1 is a perspective view of a four color screen embodying one form of the invention, and

Fig. 2 is a cross-section.

The invention can be carried out in various ways, of which only a few examples are mentioned herein. For example, the filters can be made of gelatin and colored or dyed so that the color desired is of full depth at one end and shades off to practically no color, or but very little color, at the other end.

- Examples of such shading are shown in Fig. 1, wherein B is the blue section which is darkest at the bottom and shades to practically no color at the top, R is the red section shown as darkest at the top and shading to practically no color at the bottom, G is the green section shown as darkest at the top and shading to practically no color at the bottom, while Y is the yellow section which is darkest at the right and shading to practically no color at the upper edge. K are the opaque sections between each filter section, which cover the emulsion while it is being changed.
- 15 Another filter can be made of pot-metal glass, or flash glass, that is, glass having color throughout its structure, or on one surface. These are then ground down to a wedge shape, so that the density of the color 20 is greatest at the thick end and less at the thin end. Effects due to diffraction or refraction, owing to the wedge shape of such filters, can be avoided by applying thereto similar but reversed wedge shape filters of 25 the same kind of clear glass, so that the whole filter has a uniform index of refraction, but still is graduated as to color, being heaviest at one end and with little or no color at the other, as in Fig. 2.
- 30 Also, in case it is desired to compensate for a preponderance of color rays in the light, as for instance excessive blue violet in arc light, the clear portions can be given a graduated yellow tint, either of graduated 35 yellow colored gelatin, densest at the clear portion of the filter, or by using a wedge shape colored glass similarly disposed. An example of a wedge shaped glass filter section compensated for yellow is 40 shown in Fig. 2, in which M represents the color section ground down to a point at P, and having combined therewith a compensating reversely arranged wedge at the thick end opposite the thin end of the color 45 section. Thus M may be a section of any one of the filters B, R, G, Y, above described, and O a section of a yellow colored compensating filter associated therewith for 50 correcting a preponderance of blue violet in arc light. This is especially desired in case the panchromatic film emulsion is over sensitive to violet rays, as is frequently the case. It will be understood that where yellow is used in this manner it is merely as a 55 corrective means, and not for color values, and while preferably used on all the filter sections to correct for color need not necessarily be so used. It will be obvious that 60 screens embodying this invention may be made up in many ways other than herein explained, and that they may be variously mounted on movable supports either rotary, or reciprocating, or movable bands, without departing from the scope of the invention.
- 65 It will be understood that the manner of

applying the broad features of this invention is not restricted to the specific forms herein described. For example, it may be desired to vary the screen section from full color at one end to no color in the middle 70 and then to full color at the other end, or the full color may be in the middle and shade toward each end to no color, or the clear sections may merge from one side to one fundamental color and from the other 75 side to another fundamental color. The invention can be used both in taking and projecting. The color value negatives obtained in taking are developed and printed in the usual manner, and then projected either 80 with the same screen used in taking, or with a correspondingly colored screen without the clear portions.

It will be seen that such arrangements and many others can readily be made without departing from the scope of the appended claims.

What we claim is:—

1. The method of recording a color value, 90 which consists in exposing the same panchromatic emulsion to light varying continuously during the exposure between a fundamental color component and substantially white light.

2. The method of recording a color value, 95 which consists in exposing the same panchromatic emulsion to light varying continuously during the exposure between a fundamental color component and light compensated to be substantially free of pre- 100 ponderating color constituent.

3. The method of recording a color value, 105 which consists in exposing the same panchromatic emulsion to light varying continuously during the exposure between a fundamental color component and white light compensated for blue violet contained therein.

4. The step in making photographic records, which consists in exposing each of a 110 predetermined succession of panchromatic emulsion sections through a different color filter, each color filter continuously varying between a predominant component and light substantially free of preponderating color. 115

5. The step in making photographic records, which consists in exposing each of a predetermined succession of panchromatic emulsion sections through a different color filter, each color filter continuously varying 120 between a predominant component and light compensated to be substantially free of preponderant color constituent.

6. The step in making photographic records, which consists in exposing each of a 125 succession of panchromatic emulsion sections through a different color filter, each color filter continuously varying between a predominant component and light compensated by yellow for blue violet. 120

7. In motion picture color photography employing a plurality of color value images in recurring cycles, the step which consists in recording each image of a cycle by light varying continuously during the exposure between a fundamental color component and light substantially free of preponderating color, the fundamental colors in each cycle forming substantially white. 5
10. 8. In color photography, the method of increasing the density of a record, which consists in recording a fundamental color value while simultaneously recording a varying white light value. 10
15. 9. In color photography, the method of increasing the density of a record, which consists in recording a fundamental color value while continuously weakening said color value and increasing the black and 20 white values. 20
10. In color photography, the method of increasing the density of a record, which consists in recording a fundamental color value while continuously and inversely varying the relative intensity of the color and 25 black and white values. 25
11. In color photography, the method of increasing the density of a record in a given time, which consists in recording the color values by constantly decreasing a fundamental color and constantly increasing black and white values. 30

In testimony whereof we affix our signatures in presence of two witnesses.
